DOUBLE-ACTING TWO-STROKE INTERNAL COMBUSTION ENGINE

Charles Schaefer, Langenthal, Switzerland, assignor to the firm of Sulzer Frères Société Anonyme, Winterthur, Switzerland

Application September 21, 1931, Serial No. 564,038
In Switzerland September 25, 1930

6 Claims. (Cl. 123—61)

This invention relates to double-acting two-stroke internal combustion engines and has for its object the modification of the characteristics of the ports associated with the two combustion chambers of a cylinder to compensate more fully than hitherto for the difference in characteristics between such working chambers.

In the following description and claims, reference will be made to the "area-time integral" of a port or ports. If, for a port, intervals of time (or crank angles in the case of an engine running at constant revolutions) are plotted as abscissæ against instantaneous areas of port opening as ordinates, a curve is obtained beginning and ending on the abscissa axis. The area enclosed between such curves and the abscissa axis is a measure of the charge admitted or released by such port, and will be hereinafter referred to as the area-time integral.

To show the area-time interval of ports per unit of volume of the working chamber, the same intervals of time as above are plotted as abscissæ against ordinates being a measure of the same instantaneous areas of port opening uncovered by the piston or other control member divided by the total volume of the working chamber concerned. This volume on one side of the piston is the product of cross-section and piston stroke, and on the other side of the piston is the same value reduced by the product of the cross-section of the piston rod and the piston-stroke, i. e., the volume of the piston rod.

It has previously been proposed, in engines of the type under discussion, to compensate for the difference in volumes between the two working chambers of a cylinder, occasioned by the passage of the piston rod through one of them, by reducing the area-time integral of ports associated with this chamber to a value such that the area-time integrals per unit volume of working chamber are the same for corresponding ports associated with the respective working chambers.

It has now been found that such reduction is insufficient in that, whilst compensating for the volumetric difference referred to no account is taken of the difference in combustion conditions in the two working chambers. In particular the combustion chamber traversed by the piston rod runs appreciably cooler than the other since the piston rod offers extra conduction surface and the stuffing boxes must be kept well cooled to avoid damage thereto. Thus the work done per unit volume of this working chamber is less than that obtainable in the other working chamber.

Further, with the ports functioning as previously proposed, additional losses occur since the expansion in the cooler working chamber is stopped too early and the scavenging air consumption is excessive in comparison with the work obtainable.

In addition this excess of scavenging air causes an excessive consumption of fuel and results in uneconomical running of the engine.

The present invention has for its principal object to compensate for these additional differences in characteristics between the two working chambers of the cylinder, and in contrast with previous proposals consists in a double-acting two-stroke internal combustion engine in which ports of that working chamber of the cylinder which is traversed by the piston rod have area-time integrals per unit volume of working chamber which are smaller than the similar integrals of corresponding ports in the other working chamber by an amount such that, in addition to the compensation made in the known manner for the decrease in volume of the combustion chamber owing to the presence of the piston rod, compensation is made for the unfavourable thermal conditions and the conditions governing the gas flow imposed by the presence of the piston rod.

The specified difference between ports as to their area-time integrals per unit volume of combustion chamber can obviously be established as regards the inlet ports associated with the two working chambers, or the outlet ports or both inlet and outlet ports.

Further, the means whereby this difference can be established may be various, as indicated hereinafter, but by way of example a convenient embodiment of the invention is hereinafter described and shown in the accompanying drawings, in which,

Figures 1 and 2 are graphs showing the port opening per unit volume of combustion chamber plotted against time or crank angle.

Figure 3 is a section of an engine constructed according to the present invention.

Figures 4 and 5 are graphs on the same basis as Figures 1 and 2 and illustrate the scavenging, charging and outlet processes of the construction according to Figure 3.

Figure 6 is a side view showing certain ports with the casing and valves removed.

In the diagrams, the time t , which in the case of a constant number of revolutions is proportional to the crank angle, is plotted as abscissæ. If F is used to represent the admission or outlet

opening area uncovered by the piston or other control member at each movement or at each value of crank angle, and V the real volume of working chamber as previously referred to for one side or for the other side of the piston, the ordinates

F

V

- 10 will represent the admission or outlet opening area at each moment or value of crank angle and uncovered by the piston or other control member, referred to the unit volume of the working chamber concerned. Accordingly the diagram areas enclosed by the curves, represent the area-time integral per unit volume, which is represented by

$$\int_A^Z \frac{F dt}{V}$$

- 20 The curves in Figures 1 and 2 are those for a double-acting two-stroke internal combustion engine with the usual admission and outlet ports which are controlled by the piston alone. The height of the exhaust ports is made as usual, greater to suit the pressure conditions, than the height of the admission ports. The combustion air is admitted into the working chambers of the engine through the admission ports. The piston on rising, will close the admission ports and begin to compress the combustion air contained in the working chamber. At or about the dead centre at which the ports are closed by the piston, there is injected into the highly compressed combustion air any desired fuel, which can be ignited by the compression heat alone or by means of separate auxiliary devices.

During the expansion or working stroke following the compression stroke, the combustion gases generated will expand and transmit to the piston the work contained in them. As soon as the piston begins to uncover the outlet ports, the combustion gases will be able to escape from the working chamber and afterwards when the admission ports have also been uncovered by the piston they will be completely swept out from the working chamber by the scavenging air entering through the said ports. The scavenging or combustion air which is now contained in the working chamber, will be again compressed after first the admission ports and then the outlet ports are closed by the piston, whereupon the cycle will begin again.

The curves 1 and 3 shown in full lines in Figures 1 and 2, refer to the working chamber which is not traversed by the piston rod, whilst the curves 2 and 4 shown in chain-dotted lines, belong to the other working chamber traversed by the piston rod. The dead centres corresponding to these processes in the two cylinder ends are, during the working of the engine, displaced by 180° of crank angle relatively to each other, but for clarity they are shown in the drawings as coinciding in a single point TP .

65 At the point A^3 or A^4 (Figure 2), opening of the outlet ports by the piston commences so that the combustion gases can escape from the working chamber into the exhaust gas conduit. The pre-exhaust lasts from the points A^3 or A^4 to the point O at which opening (A^1 or A^2 , Figure 1) of the air admission ports commences. The cross-section of opening of the outlet ports, which is obtained at the point O , referred to the unit volume of the chamber, is calculated in such a manner that during the time from A^3 or A^4 to O ,

the pressure of the combustion gases in the working chambers has fallen at least to the pressure of the scavenging air, in order to prevent any flowing back of the combustion gases into the scavenging air conduits. After the point O , the cross-section of the outlet ports can of course increase still further until after the ports have been completely uncovered by the piston, it reaches the value o^3 or o^4 .

10 The opening of the admission ports, which begins at the points A^1 or A^2 , starts the scavenging of the working chamber in order completely to expel from the working chamber any combustion gases still contained therein. The cross-sections of the admission openings are indicated by the curves 1 and 2, and the admission ports reach a maximum opening value o^1 or o^2 which have the same value in this case. After the dead centre has been passed, the scavenging and outlet or discharge processes take place in a symmetrical manner, but in the opposite direction, so that at the point Z^1 or Z^2 the scavenging is stopped by the closing of the admission ports, and at the point Z^3 or Z^4 the outlet ports are closed whereupon the compression of the combustion air introduced into the cylinder commences.

15 In accordance with this diagrammatic representation, the areas enclosed in Figure 1 between the curves 1 or 2 and the axis of abscissæ, represent the share of the area-time integrals (for 30 the admission of the air) per unit volume of working chamber, and the areas enclosed in Figure 2 between the curves 3 or 4 and the axis of the abscissæ, represent the area-time integral (for 35 release of combustion gases) per unit volume of working chamber.

According to the invention, the value of such integral for the outlet ports (curve 4) associated with the working chamber traversed by the piston rod, is made smaller than the value of such 40 integral for the outlet ports (curve 3) associated with that working chamber not traversed by the piston rod. Owing to this difference, the advantage is obtained that in the working chamber traversed by the piston rod, the outlet openings 45 are not opened too early, thereby avoiding a premature escape of the high pressure gases, which can still transmit work to the piston and therefore avoiding an additional loss of work caused by such escape, and this extra work is now transmitted to the crank shaft of the engine.

50 The most favourable conditions for the working chamber will be obtained when the excess of scavenging air is also adapted to the work performed per unit volume of the said working 55 chambers. As this work in the working chamber traversed by the piston rod is smaller than in the other working chamber not traversed by the piston rod, whilst the admission openings per unit volume are made the same for both working 60 chambers (curves 1 and 2, Figure 1) the reduction in the excess of scavenging air is obtained by a smaller scavenging pressure in front of the corresponding admission ports for the working 65 chamber traversed by the piston rod.

Instead of making the scavenging pressure for one working chamber lower than for the other, the same scavenging pressure may be of course used simultaneously for both working chambers, and an increase in the excess of scavenging air 70 in the working chamber not traversed by the piston rod, can be obtained, according to the invention, by an additional charging with scavenging air or by supercharging with air of higher pressure. For this purpose, separate scaveng- 75

ing air admission openings are opened at the point B (Figure 1) at the moment of, or after, the closing of the outlet ports of the working chamber not traversed by the piston rod, by lifting a control member such as for instance a valve, which admits additional or supercharging air into the cylinder until such ports are closed by the piston at C.

The diagram areas enclosed by the curves 1, 5 and 3 in Figures 1 and 2, represent the area-time integrals per unit volume of the working chamber not traversed by the piston rod, and the diagram areas enclosed by the curves 2 and 4 represent the area-time integrals per unit volume of the working chamber traversed by the piston rod. According to the invention, the areas enclosed by the chain-dotted curves 2 or 4, are smaller than the areas enclosed by the curves 1 and 5 or 3 shown in full lines.

20 The cylinder 20 of the internal combustion engine shown in Figure 3 and taken as the basis for the curves of Figures 4 and 5, is supplied with the scavenging air through a pipe 21 connected to the working cylinder 20, whilst the combustion gases generated in the cylinder, are discharged through the exhaust conduit 22. The piston 23 which is shown in full lines in the lower dead centre position, uncovers in this position for the upper working chamber 24 the noncontrolled admission port series 25, the controlled admission port series 26 and the outlet port series 27. The residue of the waste gases still contained in the upper combustion chamber 24 is expelled through the outlet ports 27 into the waste gas conduit 22 by the scavenging air entering directly through the ports 25 and the non-return valve 28.

In the upper dead centre position of the piston 23, shown in chain-dotted lines, the piston controlled admission ports 25, the admission ports 30 controlled by a valve 29 and the outlet ports 31, are uncovered in the same way for the lower working chamber traversed by the piston rod 32.

The admission ports 25, 26 and 30, as well as the outlet ports 27 and 31, are arranged symmetrically to the plane I—I at right angles to the cylinder axis. The bottom dead centre position shown in full lines, and the upper dead centre position shown in chain-dotted lines, are however arranged symmetrically to another plane II—II which is also at right angles to the cylinder axis, the two planes of symmetry I—I and II—II being parallel to each other at a distance apart u . This ensures that according to the invention the area-time integrals per unit volume of working chamber are smaller for the lower working chamber than for the upper combustion chamber 24.

For the upper end, the controlled air admission ports 26 are uncovered already at the moment A^6 , Figure 4, but as the excess of pressure of the combustion gases in the cylinder prevents the opening of the scavenging valves 28 arranged in front of the ports 26, no air will yet enter the cylinder. The corresponding outlet ports 27 are opened at the moment A^{10} Figure 5. At the moment O when the pressure in the cylinder has fallen to a sufficient extent, the scavenging valves 28 for the ports 26, as well as the ports 25, will be opened. At the moment Z^6 , the ports 25 will be closed, whilst scavenging through the air admission ports 26 will still continue during closing of the outlet ports at Z^{10} . Until the moment Z^6 , these air admission ports 26 will remain open, so that during the interval from Z^{10} — Z^6

there will take place additional charging of the working chamber 24.

The corresponding scavenging, charging and exhaust processes for the lower cylinder end, governed by the air admission ports 25 and 30 and the outlet ports 31, are represented in a corresponding manner in Figures 4 and 5 by the chain-dotted curves 7, 9 and 11. Their shape is the same as that of the curves 6, 8 and 10 shown in full lines. According to the invention, however, the areas enclosed between the axis of the abscissa and the chain-dotted curves 7, 9, 11 which correspond to the lower working chamber traversed by the piston rod, and represent the area-time integrals per unit volume, are made smaller than the corresponding areas enclosed between the axis of the abscissa and the curves shown in full lines, which correspond to the working chamber in the upper cylinder end.

If desired, the planes of symmetry I, of the ports 20 and that II of the two dead centre positions of the piston could be made to coincide. In such a case the difference in area-time integrals per unit volume of working chamber may be produced by the difference in the nature of the piston movements at or about the two dead centre positions caused by the finite length of the connecting rod. Of course the admission ports could also be given any desired shape and arrangement and if desired, the ports could be positively opened and closed in any desired manner by suitably controlled members in order to ensure additional charging or to prevent exhaust gases from entering the scavenging air conduits, or in order to ensure other special conditions of opening. If desired certain ports could be made operative both for the upper and for the lower cylinder ends.

I claim:

1. A double-acting, two-stroke, internal combustion engine, comprising a cylinder having a working chamber traversed by the piston rod, said chamber having ports, another working chamber having ports, said first ports having area-time integrals per unit-volume of the first chamber which are smaller than the similar integrals of corresponding ports in the second chamber by such an amount as to compensate for the decrease in volume of the working chamber due to the piston rod therein, and for piston-rod produced unfavorable thermal conditions and unfavorable conditions governing the gas flow.

2. A double-acting, two-stroke, internal combustion engine as in claim 1, in which the respective ports for the respective working chambers are located at or about the two dead-center positions respectively.

3. A double-acting, two-stroke, internal combustion engine as recited in claim 1, in which means are provided for establishing said difference in area-time integrals per unit-volume of combustion chamber both for the inlet ports and for the outlet ports in the respective working chambers.

4. A double-acting, two stroke, internal combustion engine as recited in claim 1, in which said ports are controlled by said piston and are arranged symmetrically about a plane disposed transversely of the cylinder axis, which plane is displaced in the direction of the cylinder axis from a second plane parallel to the first plane and positioned midway between the position occupied by the lower piston edge when in the upper dead center position and that occupied by

the upper piston edge when in the lower dead center position, such displacement being to the extent necessary to establish the specified difference in area-time integrals per unit volume of combustion chamber.

5. A double-acting, two-stroke, internal combustion engine as recited in claim 1, in which means are provided for supplying auxiliary air to that one of the working chambers which is not traversed by the piston-rod, supplying it only

10

after closure of the outlet ports for this said chamber.

6. A double-acting, two-stroke, internal combustion engine as recited in claim 1, in which means are provided for rendering the pressure of the scavenging air for the working chamber traversed by the piston-rod, lower than that at which scavenging air is supplied to the other combustion chamber.

CHARLES SCHAER. 10
